UNITED STATES PATENT OFFICE.

CLINTON H. WENTWORTH AND LLOYD H. WALLNER, OF LOS ANGELES, CALIFORNIA;
SAID WALLNER ASSIGNOR TO SAID WENTWORTH.

RADIATOR.

Application filed May 17, 1923. Serial No. 639,532.

To all whom it may concern:

Be it known that we, CLINTON H. WENTWORTH and LLOYD H. WALLNER, both citizens of the United States, residing at Los Angeles, in the county of Los Angeles and State of California, have invented a new and useful Radiator, of which the following is a specification.

This invention relates to radiators and is particularly directed to that general type of radiator adapted for use as a unit of the water cooling system of a motor vehicle.

It is an object of this invention to provide a radiator having a removable core unit capable of being removed from or inserted in the radiator framework through the front opening therein, whereby a replacement of the core may be accomplished without bodily removing the entire radiator from the machine.

It is a further object to provide a radiator structure of this nature in which the requirement for an outer finish shell is obviated, and in which the manifolds form a part of the finished framework of the radiator.

Another object is to provide a radiator having a contour flange defining the shape of the upper portion of the front opening in the radiator framework, and having a core unit adapted to be inserted or removed through said front opening by first having its upper end inserted beneath said contour flange and its lower end then moved rearwards to place.

Various other objects and advantages will be more fully apparent from the following description of the accompanying drawing, which forms a part of this disclosure, and which illustrates a preferred form of embodiment of the invention.

Of the drawings:

Fig. 1 is a front elevation of a radiator constructed in accordance with the present invention.

Fig. 2 is a top plan view.

Fig. 3 is a plan section on line 3-3 of Fig. 1.

Fig. 4 is a plan section on line 4-4 of Fig. 1.

Fig. 5 is a central vertical section.

Fig. 6 is a front elevation of one of the interchangeable core sections.

Fig. 7 is an enlarged plan view of one of the end castings of a core section.

In the drawings is illustrated an automobile radiator in which the upper manifold A and the lower manifold B, are separate castings and are joined together by side members C to form a complete framework adapted to receive the detachable core, indicated generally by the reference character D.

It is usual in radiator construction, to first construct the manifolds and core and to then place such completed structure within a shell of sheet metal, the shell being of the desired contour and finish to harmonize with the general design and finish of the automobile. The front wall of the usual radiator shell is of more or less ornamental contour and to a certain degree overlaps the front side of the radiator core, making it impossible to remove the core through the front opening in the shell, even in instances where a removable core is provided. It will be evident that in a radiator having a removable core which can only be removed from the rear side, such removal cannot be accomplished without first bodily removing the entire radiator from the machine, due to the fact that in ordinary automobile construction the engine is positioned too close to the radiator to otherwise permit a removal of the radiator core.

Further, in contemplating the removal and insertion of a core through the front opening of the shell of a radiator, it will be evident that unless special provisions are made, the front opening would have to be of the same shape and size as the core. This would necessitate a separate size and shape of core for every size and design of radiator.

It is a purpose of the present invention to provide a radiator which does not require a shell and which has a core unit capable of being removed and replaced by another similar unit, without removing the radiator from the machine.

To this end the upper manifold A has an exterior contour conforming to the desired finished contour of the upper portion of the radiator and has opposite limbs 10 to which the channel side members B are secured preferably by bolts 11, the lower ends of the members B embracing and being

secured to the lower manifold C by bolts 12. This provides a substantial rigid framework having a finished exterior surface, it of course being understood that the 5 upper manifold A may be of other exterior shape than the rounded form shown.

The upper manifold A has the usual filling opening 13, an inlet port 14 and a relatively short baffle web 15 just above the inlet port. The lower rear wall 16 has, in this 10 instance, three ports 17 which are adapted to register with the inlet openings of the core.

The lower manifold C has an outlet port 18 (see Fig. 4) and its front wall 19 has 15 three ports 20 which are adapted to register with the lower outlet opening of the core.

In the present instance it is preferable to form the core D of a plurality of separate sections 21, there being three of such sections 20 shown. These core sections are of uniform construction and are therefore interchangeable one with another. Each comprises opposed vertical side plates 22 and an intermediate honey-comb structure providing a 25 plurality of more or less vertical water channels and intermediate horizontal air spaces, this intermediate core structure as shown being only for the purpose of illustration as it is evident that any of a large number of 30 specific core constructions may be utilized. Secured to the opposite ends of each core section 21, preferably by soldering, are terminal castings 23 and 24 which are of duplicate form but which are reversed as to relative 35 position.

Each casting 23 provides a shallow chamber 23^a of sufficient size to communicate with the upper ends of all of the water channels of the respective core structure, and has an 40 upwardly extending inlet branch 23^b terminating with a vertically disposed flange 23^c adapting it to be attached to the rear wall 16 of the upper manifold A by bolts 25, and with its inlet branch 23^b in registry with the 45 respective port 17 (see Figs. 3 and 5). Each casting 24 likewise provides a shallow chamber 24^a communicating with the lower ends of all of said water channels and has a downwardly extending outlet branch 24^b terminating 50 with a vertically disposed flange 24^c adapting it to be attached to the front wall 19 of the lower manifold C by bolts 26, and with its outlet branch 24^b in registry with the 55 respective port 20, (see Figs. 4 and 5). It will of course be understood that between the several flanges 23^c and 24^c and the manifolds there will be provided suitable gaskets to insure water tight joints.

With this structure the bolts 25 which 60 secure the core units or sections 21 to the upper manifold A are easily accessible from the rear side of the radiator, while the bolts 26 which secure said sections to the lower manifold C are easily accessible from the front 65 side of the radiator.

When it is desired to remove a core section the bolts 25 and 26 of said section are removed and the lower end of the section is then pulled forward, as indicated in dotted lines in Fig. 5, after which the section will 70 easily drop out, a replacement of a section being accomplished in a reverse manner.

This construction permits the upper manifold A to be provided with a contour flange 28 overlapping the upper ends and outer 75 corners of the core D, and which may be of any desired shape without in any way interfering with the replacement of the core sections.

From the above it will be evident that we 80 have provided a radiator in which the framework comprising the manifolds and side members present a finished appearance without requiring an outer shell, and in which the core may be removed through the front 85 opening of the radiator so as to render it convenient and easy to replace a worn out core with a new core without first removing the entire radiator from the machine, the core sections being so formed as to be bolted 90 at their upper ends to a rear vertical wall of the upper manifold and at their lower ends to a front vertical wall of the lower manifold.

While the form of construction herein 95 illustrated and described is fully adapted to fulfill all of the objects primarily stated, it is to be understood that we do not wish to limit the invention in this regard, for it is susceptible of embodiment in various other 100 forms, all coming within the scope of the following claims.

We claim:

1. A radiator comprising a finished framework including an upper manifold, a 105 lower manifold, and connecting side members, and a core unit adapted to be inserted or removed through the front opening in said framework and having its upper end secured to a rear wall of the upper manifold and its lower end secured to a front 110 wall of the lower manifold.

2. A radiator comprising a finished framework including an upper manifold having opposed depending limbs, a lower 115 manifold, and side members connecting said limbs with the lower manifold, and a core unit adapted to be inserted or removed through the front opening in said framework, the core unit being secured to the upper manifold by bolts accessible from the rear of the radiator, and to the lower manifold by bolts accessible from the front of the radiator.

3. A radiator comprising a finished 125 framework including an upper manifold, a lower manifold, and connecting side members, and a core unit adapted to be inserted or removed through the front opening in said framework and having its upper end 130

secured to the upper manifold by means accessible only from the rear of the radiator and its lower end secured to the lower manifold by means accessible only from the front 5 of the radiator.

4. A radiator comprising a finished framework including an upper manifold, a lower manifold, and connecting side members, and a removable core unit positioned 10 within said framework and secured to a rear wall of the upper manifold and to a front wall of the lower manifold, the upper manifold having an inwardly projecting contour flange extending over the upper end and 15 corners of the core unit.

5. A radiator comprising a finished framework including an upper manifold, a lower manifold, and connecting side members, and a removable core unit positioned 20 within the framework and including opposed terminal members at its upper and lower ends, the upper terminal member being secured to a rear wall of the upper manifold and the lower terminal member 25 being secured to a front wall of the lower manifold, whereby the core unit may be removed through the front opening in the framework.

6. A core unit for a radiator, comprising 30 a core having a plurality of water channels, and opposed terminal members at opposite ends of said core each having a passage communicating with the several channels and a vertically disposed flange adapted to be secured to a radiator manifold, the flange of one member facing in one direction and the flange of the other member facing in an opposite direction.

7. A radiator comprising a framework 40 including an upper manifold, a lower manifold and connecting side members, and a removable core unit secured to the rear wall of one manifold and to the front wall of the opposite manifold, said manifolds and 45 core unit having communicating ports and being formed to permit a removal of the core unit through the front opening in the framework.

8. A radiator comprising a framework 50 including an upper manifold, a lower manifold and connecting side members defining a front opening, and a core unit of greater height than the height of said opening and having opposite terminal members, the up-

per terminal member engaging the rear vertical wall of the upper manifold and the lower terminal member engaging the front vertical wall of the lower manifold, the manifolds and core unit being formed to permit a removal of said core unit through 55 said front opening by first drawing the lower end of said unit forwardly through the opening to tilt said unit and subsequently lowering said unit to disengage it from the upper manifold and remove it from the 60 framework.

9. A radiator comprising an upper manifold, a lower manifold and connecting side members forming a normally rigid framework having a front opening, and a core 70 unit of greater height than the height of said opening and having opposite terminal members normally engaging and detachably secured respectively to the rear wall of one manifold and the front wall of the other 75 manifold, one manifold having a contour flange extending inwardly in front of the upper portion of the core unit, said manifolds and terminal members being formed to permit a removal of the core unit for 80 wardly through said front opening with the framework remaining in normal condition.

10. A radiator comprising an upper manifold, a lower manifold and connecting side members forming a normally rigid 85 framework having a front opening, and a plurality of core units positioned side by side within the framework, each core unit being of greater height than the height of said front opening and having opposite terminal members normally engaging and detachably secured respectively to the rear wall of one manifold and the front wall of the other manifold, one manifold having a contour flange extending inwardly in front of 90 said core units, said manifolds and core units being formed to permit an individual removal of a core unit forwardly through said front opening, with the framework and the others of the several core units remaining 95 in normal condition.

Signed at Los Angeles, California, this 11th day of May, 1923.

CLINTON H. WENTWORTH.
LLOYD H. WALLNER.
